UNITED STATES PATENT OFFICE.

ZACHARY E. RUSSELL, OF ST. CLOUD, MINNESOTA, ASSIGNOR TO CLYDE W. WARREN,
SAUK RAPIDS, MINNESOTA.

**PAINT OR STAIN MIXING AND COATING APPARATUS FOR PORCH SHADES AND THE
LIKE.**

Application filed June 29, 1925. Serial No. 40,248.

To all whom it may concern:

Be it known that I, ZACHARY E. RUSSELL, a citizen of the United States, residing at St. Cloud, in the county of Stearns and State of Minnesota, have invented certain new and useful Improvements in Paint or Stain Mixing and Coating Apparatus for Porch Shades and the like; and I do hereby declare the following to be a full, clear, and 10 exact description of the invention, such as will enable others skilled in the art to which it appertains to make and use the same.

My present invention has for its object to provide a mixing and coating apparatus intended for general use in applying paint, stain or other liquid to articles by a dipping process and particularly for applying the same to porch shades of the type made up of strips of thin wood connected by 20 cords.

To the above end, generally stated, the invention consists of the novel devices and combinations of devices hereinafter described and defined in the claims.

In the accompanying drawings, which illustrate the invention, like characters indicate like parts throughout the several views.

Referring to the drawings:

Fig. 1 is a fragmentary plan view of the apparatus with some parts sectioned and some parts removed;

Fig. 2 is a view partly in front elevation and partly in longitudinal vertical section, taken on the line 2—2 of Fig. 1;

Fig. 3 is a view principally in left-hand end elevational on an enlarged scale;

Fig. 4 is a transverse vertical section taken on the line 4—4 of Fig. 1;

Fig. 5 is a fragmentary detail view with some parts sectioned on the line 5—5 of Fig. 1, on an enlarged scale; and

Fig. 6 is a detail view in plan with some parts sectioned on the line 6—6 of Fig. 2.

The numeral 10 indicates a kettle-like open supply tank which, as shown, is set into a floor 11 for holding a liquid such as paint, stain or other surface coating material. A long skeleton frame 12 is supported on the floor 11 with one of its ends 50 extending over the supply tank 10. Mounted in the frame 12, at the transverse center thereof, is a longitudinally extended dipping trough 13 that is segmental in cross section

and extends radially outward from the supply tank 10. In the inner or delivery end of the dipping trough 13, at the bottom thereof, is a discharge port 14 of such size as to maintain a certain level of the liquid X in said dipping trough. This port 14 55 discharges into the receiving end of an inclined return spout 15 arranged to empty into the supply tank 10.

The dipping trough 13 is supplied with the liquid X from the supply tank 10 60 through a pipe 16 by a rotary pump 17, of any suitable design. This pipe 16 leads from the casing of the pump 17, empties into the dipping trough 13 at the receiving end thereof and is provided with a slip joint 18 65 and a separable joint 19 for a purpose that will presently appear. It may be here stated that the pump 17, pipe 16, dipping trough 13, port 14 and spout 15 afford a 70 circulating system through which the liquid X is conveyed from the supply tank 10 to the dipping trough 13 and then returned to said tank from said trough.

The pump 17, as an entirety, is carried on the lower end of its driving shaft 20 and which shaft has keyed to its upper end portion a long cylinder which affords a driving pulley 21. Said shaft 20 at the ends of the pulley 21 is journaled in a supplemental frame 22 having a pair of laterally spaced 80 oblique guide rods 23 which extend parallel to the axis of said shaft and are slidably mounted in fixed bearing heads 24 on a tubular cross-tie bar 25 on the frame 12. The supplemental frame 22 supports the 85 pump 17, by its shaft 21, for oblique movement into and out of the liquid X in the supply tank 10. The purpose of thus mounting the pump 17 is to position the same substantially in the center of the supply tank 90 10 at the bottom thereof when in an operative position and to not interfere with an agitator, as will presently appear, when the pump 17 is lifted from the liquid X.

For supporting the pump 17 at different elevations, I provide a counterbalancing device in the form of a weight 26 attached by a chain 27 to the supplemental frame 22 near the lower end thereof, as shown in 95 Fig. 3.

This chain 27 runs over a guide sheave 28 100 on a cross-tie bar 29 secured to the upper

ends of outer and intermediate guide posts 30 which rest on the floor 11 and are secured to the frame 12 at the back thereof. A portion of the chain 27, above its connection 5 with the supplemental frame 22, is held parallel to said frame by a sheave 31 journaled in a bearing 32 on the supplemental frame 22. The counterweight 26 has formed in its 10 sides vertical grooves 33 into which the left-hand and intermediate posts 30 extend for guiding said weight during its raising and lowering movement.

In addition to the circulation of the liquid X for keeping said liquid mixed and of the 15 same consistency, I mount in the supply tank 10 an agitator 34 in the form of a segmental bar. This agitator 34 has substantially the same contour as the bottom of the supply tank 10 and when in operation works close to 20 the bottom of said tank. Said agitator 34 is secured to the lower end of an upstanding shaft 35 journaled in an upper bearing 36, intermediate bearing 37, and a lower bearing 38. Said upper bearing 36 is rigidly 25 secured to a bracket 39 on the frame 12, the intermediate bearing 37 is rigidly secured to a cross-tie bar 40 on said frame and the lower bearing 38 is carried by and forms a part of a cross-head frame 41 mounted in 30 notched-like seats 42 in the bearings 36 and 37 for vertical sliding movement. The upper end of the agitator shaft 35 is further journaled in a gear casing 43 carried by the upper end of the cross-head frame 41 35 and having mounted therein a gear 44 keyed to said shaft.

The cross-head frame 41, agitator 34 and all other parts carried thereby are held where set by a counterweight 45 connected 40 by a chain 46 to the cross-head bearing 38 and which chain runs over a guide sheave 47 on the cross-tie bar 29. This counterweight 45 has in its sides grooves 48 into which the right and intermediate posts 30 extend and 45 guide said counterweight.

Mounted in the frame 12 under the dipping trough 13 is a hopper-like pan 49 in the bottom of which is a liquid-collecting trough 50 that is inclined toward the supply 50 tank 10 and has in its discharge end a port 51 which empties into an inclined spout 52 arranged to discharge into said tank. At the front of the dipping trough 13 on the frame 12 is a skeleton support 53 in the form 55 of a plurality of edgewise spaced bars that extend transversely in respect to said dipping trough, and their front ends are secured downwardly and inwardly. The inclined back of the pan 49 extends materially 60 above the frame 12, and between said back and the dipping trough 13 on the frame 12 is a drain rack 54 in the form of edgewise spaced bars that extend transversely in respect to the dipping trough 13 and their 65 rear end portions are extended upward and

rigidly secured to said back. It may be here stated that the support 53 and drain rack 54 are located in the same plane and above the dipping trough 13.

For dipping a porch shade Y, made up of 70 thin strips of wood connected by cords, and conveying the same through the liquid X in the dipping trough 13, I provide a plurality of edgewise spaced belts 55 in the form of sprocket chains arranged to run transversely 75 through the dipping trough 13 and over front sprocket wheels 56, keyed to a long shaft 57, and rear sprocket wheels 58 keyed to a long shaft 59. The shafts 57 and 59 are journaled in bearings in the ends of the 80 hopper-like pan 49. The sprocket wheels 56 are located at the rear edge of the support 53, forward of the dipping trough 13, and the sprocket wheels 58 are located at the front edge of the drain rack 54 and rearward of said trough. Said sprocket wheels 56 and 58 are so located that the outer faces of the belts 55 in passing thereover are flush with the upper surfaces of the support 85 53 and drain rack 54.

To hold the belts 55 during their travel between the sprocket wheels 56 and 58 so that they move through the liquid X in the dipping trough 13 and at the same time hold the porch shade Y on the belts 55, I provide 90 a plurality of axially spaced rollers 60 located directly over said belts and secured to a relatively heavy tubular shaft 61. On the ends of the shaft 61 are trunnions 62 journaled in vertical floating bearings 63 having 100 fork-like sides 64 which interlock with pairs of guide posts 65 secured to the end members of the pan 49, and guide said bearings during their floating movements. The rollers 60 bear directly on the porch shade Y, 105 as the same is conveyed through the dipping trough 13 and hold the same on the belts 55. Each pair of guide posts 65 is connected at their upper ends by a tie bar 66.

To prevent the porch shade Y from winding on the rollers 60 after having passed through the dipping trough 13, there is secured to the front guide posts 65 a skeleton guard 67, the lower edge of which extends below the tops of said rollers and rearward 115 thereof.

For guiding the belts 55 during their travel between the sprocket wheels 56 and 58, and under the dipping trough 13, there is provided an idle sprocket wheel 68 for 120 each of said belts 55. Said sprocket wheel 68 is loosely journaled on the free end of the long arm of a lever 69 intermediately fulcrumed to a bearing 70 on an angle bar 71 secured to the ends of the pan 49, and the short end of said lever is yieldingly held raised by a coil spring 72 anchored at 73 to the pan 49.

Obviously, the springs 72 are under strain 125 to depress the sprocket wheels 68 to take the 130

slack out of the belts 55 and hold the same against the porch shade Y during its travel under the rollers 60.

To operate the pump 17 and agitator 34 and drive the belts 55 and rollers 60, there is mounted on the frame 12 an electric motor 74 having on its armature shaft a pulley 75 and a worm 76. A belt 77 runs over the pulleys 21 and 75 and drives the pump 17. The purpose of the long pulley 21 is to permit the required raising and lowering movements of the pump 17. The worm gear 76 meshes with a worm gear 78 to which is secured an axially aligned gear 79 that meshes with the gear 44 and drives the agitator 34 when lowered into the supply tank 10, as indicated by broken lines in Fig. 2. When the agitator 34 is raised out of the liquid X in the tank 10, the gear 44 is moved out of mesh with the gear 79 and thereby stops the driving action of said agitator. The shaft 59 is provided with a worm pinion 80 which meshes with the worm 76 and drives said shaft and the belts 55, which run over the sprocket wheels 58, thereon. By reference to Fig. 1, it will be noted that in place of a roller 60 for the left-hand belt 55, there is a co-operating sprocket wheel 81 which drives the shaft 61 and hence the rollers 60, which co-operate with the belts 65 for conveying the porch shade Y through the liquid X in the supply tank 10.

A casing 82 is provided for the worm 76, worm gear 78, gear 79 and worm pinion 80, and which casing 82 and the casing 43 are open at their opposing sides to permit the gear 40 to be moved axially into and out of mesh with the gear 79.

Operation.

To paint, stain or otherwise coat the porch shade Y with the liquid X, the same is preferably rolled and placed on the support 53 and the outer longitudinal edge thereof inserted between the belts 55 and rollers 60 and when caught therebetween will be conveyed through said liquid and deposited on the drain rack 54. The weight of the rollers 60 and shaft 61 in such as to hold the belts 55 depressed in the liquid X so that the porch shade Y will be submerged therein, as shown in Fig. 5. All of the surplus liquid X drained from the porch shade Y when on the drain rack 54 will be precipitated into the pan 49, as well as any splash or overflow from the dipping trough 13, and collected in the trough 50 and conveyed back into the supply tank 10 through the port 51 and spout 52.

The circulating system for the liquid X, which includes the dipping trough 13 and pump 17, with the assistance of the agitator 34, will keep the liquid X in constant mo-

tion during the operation of the apparatus so there will be no sediment thus eliminating waste, and at the same time the liquid X will always be of the same consistency. The action of the agitator 34 may be stopped, at will, simply by raising the same to move its gear 44 out of mesh with the gear 79 and which agitator is held where set by its counterweight 45. The pump 17 may be set at different elevations in the liquid X or raised entirely out of the same and held where set by its counterweight 26. Due to the long pulley 21, the pump 17 will be continuously driven, irrespective of its elevation, by the belt 77. By mounting the pump 17 and agitator 34 for lifting movements out of the liquid X, the work of cleaning the supply tank 10, pump 17 and agitator 34 or making repairs is greatly facilitated.

In case it is necessary to clean the dipping trough 13, belts 55 and roller 60, the shaft 61 may be lifted out of said trough and held suspended by cables or the like secured in notches 83 in the upper ends of the rear guide posts 66.

Before the pump 17 can be raised, it is necessary to separate the pipe by moving its intermediate vertical section in the slip joint 18 to disconnect the joint 19, as shown in Fig. 3. By mounting said pump 17 for oblique raising and lowering movements, the same, when lowered, is at substantially the center of the supply tank 10 and when raised moves away from the cross-head frame 41 so as to not interfere therewith. In addition to the bearings in the ends of the pan 49 for the shafts 57 and 59, bearings therefor are formed in a plurality of transverse bars 84 which form parts of said frame. The intermediate portions of the bars 84 are depressed to form saddles on which the dipping trough 13 rests.

The above described apparatus has, in actual usage, proven highly efficient for the purpose had in view, and has resulted in a large saving in the amount of coating material used and time required in applying the same to a porch shade, and at the same time, the coating material is evenly applied.

What I claim is:

1. The combination with a dipping trough, of endless belts for conveying a shade through the trough, and a floating shaft having a plurality of rollers arranged to directly rest on the shade and hold the same on said belts.

2. The structure defined in claim 1 in further combination with means for driving said shaft.

3. The combination with a dipping trough, of pairs of horizontally laterally spaced wheels, endless belts arranged to run over said wheels, and a floating pressure device extending between said pair of wheels and

arranged to directly engage a shade and press the same onto said belts.

4. The structure defined in claim 3 in further combination with a yielding slack take-up device for each belt.

5. The combination with a dipping trough, of pairs of horizontally laterally spaced wheels, endless belts arranged to run over said wheels, and a floating shaft extending between said pairs of wheels and having rollers arranged to rest directly on a shade and hold the same on said belts to be conveyed thereby through the trough.

6. The combination with a dipping trough, of pairs of horizontally laterally spaced wheels, endless belts arranged to run over said wheels, and a floating shaft extending between said pairs of wheels and having rollers arranged to rest directly on a shade and hold the same on certain of said belts to be conveyed thereby through the trough, said shaft having a wheel engaging one of the belts to drive said shaft.

7. The combination with a liquid supply tank, of a main frame, a dipping trough, a liquid circulating system including a pump for supplying the trough with liquid from the tank and returning the same to the tank from the trough, a vertically adjustable cross-head frame mounted on the main frame, and an agitator carried by the cross-head frame for a movement into and out of the liquid in the tank.

8. The structure defined in claim 5 in further combination with transmission mechanism for the pump including a driven member on the pump journaled in the supplemental frame and in constant operative connection with the transmission mechanism irrespective of the elevation of the pump.

9. The combination with a liquid supply tank, of a main frame, a dipping trough, a liquid circulating system including a pump for supplying the trough with liquid from the tank and returning the same to the tank from the trough, a vertically adjustable supplemental frame mounted on the main frame, said pump being carried by said supplemental frame for a movement into and out of the liquid in the tank, and transmission mechanism for the agitator including co-operating driving and driven gears, the latter of which is on the agitator and out of mesh with the former gear when the

cross-head frame is raised, said driven gear being arranged to be moved into mesh with the driving gear during a downward movement of the cross-head frame to project the agitator into the liquid in the tank.

10. The combination with a dipping trough, of pairs of horizontally laterally spaced wheels, endless belts arranged to run over said pairs of wheels, a floating shaft extending between said pairs of wheels and having rollers arranged to rest directly on a shade and hold the same on said belts to be conveyed thereby through the trough, said shaft and its rollers having such pressure as to hold the belts depressed between the pairs of wheels, and slack take-up devices operative on said belts below said pairs of wheels.

11. The combination with a dipping trough, of a pair of horizontally laterally spaced shafts, pairs of aligned sprocket wheels on said shafts, endless sprocket chains arranged to run over the sprocket wheels, a floating shaft extending between said two shafts and having rollers arranged to rest directly on a shade and hold the same on the sprocket chains to be conveyed thereby through the trough, and a sprocket wheel on the floating shaft and engaging one of the sprocket chains to drive the floating shaft, said floating shaft and its rollers having such pressure as to hold the respective portions of the sprocket chains depressed between said pairs of shafts.

12. The structure defined in claim 11 in further combination with individual yieldingly held sprocket wheels engaging the sprocket chains below said pair of shafts for taking up the slack therein.

13. The combination with a liquid supply tank, of a dipping trough, a liquid circulating system including a pump for supplying the trough with liquid from the tank and returning the same to the tank from the trough, a drain rack at the delivery side of the dipping trough, and a liquid collecting trough under said rack and arranged to discharge into the supply tank.

14. The structure defined in claim 13 in further combination with a shade support at the receiving side of the dipping trough.

In testimony whereof I affix my signature.

ZACHARY E. RUSSELL.
